UNITED STATES PATENT OFFICE.

SIDNEY S. GUTLON, OF ALLSTON, MASSACHUSETTS.

DESIGN FOR A NET FABRIC.

Application filed July 30, 1928. Serial No. 27,614. Term of patent 3½ years.

To all whom it may concern:

Be it known that I, SIDNEY S. GUTLON, a citizen of the United States, residing at Allston, in the county of Suffolk and State of Massachusetts, have invented a new, original, and ornamental Design for Net Fabrics, of which the following is a specification, reference being had to the accompanying drawing, forming part hereof.

The figure is a partial plan view of a piece of net fabric showing my new design.

I claim:

The ornamental design for a net fabric as shown.

Signed by me at Boston, in the county of Suffolk, and State of Massachusetts, this 28th day of July, 1928.

SIDNEY S. GUTLON.
